ALLAN F. HUNT, OF BURLINGAME, CALIFORNIA

CARD INDEX

Application filed November 3, 1930. Serial No. 493,002.

This invention relates to an index adapted to be used in conjunction with a telephone or the like or in other situations where a card index for ready reference may be desired.

It is recognized that there are various forms of indexes for telephone numbers, street addresses and the like, now in use, such as books with indexed edges and ordinary file cards arranged in side by side relation; but these, generally, are inconvenient to handle; are frequently inaccessible when reference thereto is desired, or where bound in book form have a tendency to shut from spring action of the binding just at the time it is desired that the index should remain open for reference.

While this invention may be utilized for other purposes, it is desirable and illustrated herein with reference to its use for telephone numbers.

Frequently, a telephone number is called or dialed and there is a delay in making connection with the number called, or the central operator asks for a repeat number or a re-dialing, and in the meantime the ordinary type of index has closed or the telephone number called has been forgotten.

Some of these index devices are difficult to operate with one hand, especially when a party finds it necessary to hold the telephone instrument in one hand, or to hold a pencil to write down a message.

The primary object of this invention is to provide an index which is conveniently arranged for instantaneous reference and which may be, if desired, secured to the mouth-piece of the telephone of the well known vertical type or mounted on a standard or other supporting member in connection with the French type of telephone wherein both ear piece and mouth piece are combined in a single structure.

A further object is to provide an index comprising a series of index cards pivoted on a frame and having tabs bearing one or more reference characters indicating the subject-matter appearing on the respective cards; to provide for limiting the extent to which said cards may be removed from the index; to provide a guide for each card so

that it will resume its proper place in the index after being used; to provide a frame within which said index may be mounted and to improve, generally, upon the present type of devices herein described.

With the above mentioned and other objects in view, the invention consists in the novel construction and combination of parts hereinafter described, illustrated in the accompanying drawing and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawing, wherein:

Fig. 1 is a front elevation of the frame and index with one card raised.

Fig. 2 is a side elevation showing a method of securing the index to a telephone transmitter, which latter is shown in dotted lines.

Fig. 3 is a sectional view taken on lines 3-3 of Fig. 1, with a telephone mouth-piece shown in dotted lines.

Fig. 4 is a side elevation of the index adapted to a French type telephone, smoking stand, desk or other base support.

Referring more particularly to the drawing, wherein like characters of reference designate corresponding parts, 10 indicates a frame member generally, having a rear plate 11 and a front plate 12, which are secured in spaced relation by screws 13, 13^a and 13^b, which preferably mount spacers or bushings 14. Formed on the outer edge of the periphery of the rear plate 11 are means to attach the frame to the transmitter of a well known type of telephone, preferably consisting of clips 15 which are desired to be of spring metal so that the index may be readily placed on or removed from its mounting. These clips are made to fit tightly over the bead 16 which is usually provided on the forward face of the transmitter 17.

For use with the type of telephone shown in Figs. 1, 2 and 3, an opening 18 is provided in the center of the rear plate 11 of such

diameter as to allow only the threaded portion 19 of the mouth piece 20 to pass therethrough; thereby not only will the index be supported by the clips 15 but also by the mouth piece which is removably threaded into the transmitter housing.

The front plate 12 is provided with a centrally disposed opening therein, axially aligned with the opening 18 to allow the rear portion of the mouth piece 20 to pass therethrough. It is preferred that a tight fit shall be made between the frame members 11 and 12 and the telephone transmitter and mouth piece to firmly position the index.

15 Pivottally mounted in side by side relation on a suitable mounting member, such as screws 13^a and its bushing 14 are a series of index cards 22, preferably all pivoting on the same bushing. These cards are provided 20 on the outer perimetric edge with projecting portions or tabs 23 which provide space for one or more reference characters indicating the subject matter on the particular card, and in the illustration of the preferred 25 exemplification are shown as letters of the alphabet, indicating the first letter of the names of parties whose telephone numbers or addresses appear on that card.

The tabs 23 are preferably so formed that 30 one of their projecting edges is of greater length than the other, as at 23^a, so that when the tabs are manually manipulated, usually by a finger of the hand of the operator, the next adjoining tab will not be caught by 35 the finger, and thus pull out two cards.

It is also desired that the tabs shall overlap 40 on adjoining edges, as shown at 23^b, as this furnishes a reinforcement to the tabs and prevents them from becoming bent by use, so as to interfere with their resuming their proper place in the index after being referred to.

When not in use, the cards are normally in side by side relation within the frame 10, the peripheral edge of each card substantially in 45 transverse alignment with the periphery of the frame and the index tabs extending radially therebeyond.

A stop member 24 is provided transversely athwart the frame adjacent the pivotal 50 mounting of the cards on the bushing of screw 13^a, and this portion of each card is so arranged that a portion of the card 25 will contact this stop member and thus limit the outward pivotal movement of the card.

55 In the adaptation herein illustrated, a guide member or finger 26 is provided for each card which is of sufficient length that it remains within the perimeter of the card series when the card is pivottally moved radially outward, as best shown in Fig. 1, this finger providing a guiding means whereby each card is returned to its proper place in the series. When used with the type of telephone illustrated in Figs. 1, 2 and 3, the central portion 60 of the card is cut away, as at 27, somewhat in

ogee form, so as to provide for the insertion of the telephone mouth piece to be inserted through the openings 18 and 21. This form of cut out is not essential when the index is used with a French type of telephone, or in other cases where it is not necessary to provide an opening centrally through the cards. Nevertheless, this form is preferred in all cases, since it permits of standardization in manufacture, serves to more evenly balance the card on its pivot when it is in its outward operative position, as shown on the card "EF" in Fig. 1, so that it does not fall back into place within the series by gravitation of its own weight, and this form answers every practical purpose of a guide means which would be provided by a card in which the central cut out was not made. Each card of the series is provided with a portion 28 inset from its periphery which rest in transverse alignment on the bushing of screw 13^b when the cards are normally at rest within the frame.

In Fig. 4, the cards 22 and frame 10 are shown mounted on a vertical standard 29 mounted on the base member 30 of a French type telephone, in which case the means for mounting the index on the standard may be of any suitable well known type, such as screw 31 passing through the upper end of the standard and threadedly received in socket 32 on the frame. Obviously, this type of standard could be adapted for attachment to a smoking stand, desk, or other convenient base support.

The cards may be adapted by any suitable means to be removed so that they may be replaced by new cards upon becoming mutilated or for the purpose of adding new data thereon, or for the insertion of a duplicate card when one card is filled with data, as, for example, a duplicate "EF" card may be inserted next abutting the "EF" card shown in Fig. 1, and may be given a divisional index character such as "EF²". This removability is preferably accomplished by means of a slot 33 extending from the peripheral edge of card 22 inwardly into the body of the card, so that the end of slot is offset from a radial center point 35 indicated by RC in Fig. 1, which point need not in fact be a part of the card. (See Fig. 1.) The slot is provided with edges having an ogee curve, as at 34, the slot terminating at the portion of the card mounted on the pivotal bearing 13^a.

Having thus described the invention what is claimed as new and desired to be protected by Letters Patent is:—

1. An index comprising a series of cards removably and pivottally mounted in side by side relation, and each having an index tab mounted on the respective peripheries thereof, means whereby the pivotal movement of said cards may be stopped in either direction, the index tabs on said cards each having

one radial edge of greater length than its other radial edge.

2. A device of the character described, comprising a bearing member, a plurality of cards each having an index tab extending from the peripheral edge thereof, said cards being arranged in a series in side by side relation and having pivotal bearing in common on said bearing member, a stop member adapted to align said cards in side by side relation when normally at rest in said series, a second stop member adapted to limit the pivotal movement of said cards outward from the body of the series, each of said cards being provided with a guide portion which remains within the series when the respective card is moved pivotally outward from the series, said guide portion being spaced from the portion mounted on said bearing.
- 20 3. An index comprising a plurality of cards disposed in side by side relation and each having an index tab mounted on its periphery, a common bearing member on which said cards have pivotal mounting, a stop member adapted to align said cards in side by side relation when normally at rest in series, and a second stop member adapted to limit the outward movement of said cards on said bearing member, said peripheral tabs being relatively arranged so as to form an arcuate series and being provided with a portion of the outward peripheral edge extending beyond the adjacent portion of the peripheral edge of the tab of a next adjoining card.

4. An index comprising a frame having spaced apart faces, a bearing mounted between said faces, a series of cards mounted pivotally in common in facial side by side relation on said bearing, each of said cards having an index tab mounted on its periphery, said cards being provided with guide portions to align the path of said cards in pivotal movement in the series, and means to limit the pivotal movement of said cards in either direction.

In testimony whereof I have affixed my signature.

ALLAN F. HUNT.
